METHOD OF MAKING ENAMELED
RADIATORS

Rudolph W. Loeffler, Baltimore, Md.

Application February 18, 1932, Serial No. 593,716

5 Claims. (Cl. 29—157.3)

In accordance with the present practice the great majority of heating radiators for steam and hot water systems are made of cast iron. These radiators are defective in their operation and undesirable for several reasons. The production of the hollow castings which are necessary for their construction is expensive, the radiators are heavy to ship and handle and they are also brittle and subject to failure on account of freezing, and by cracking due to blows or shocks.

On account of the thickness which is necessary to sufficient strength, they are very slow to heat resulting in a considerable loss of efficiency and are correspondingly slow in responding to control, automatic or manual. Further, it is difficult to so finish the external surface as to avoid accumulation of dirt so that they are apt to be unsanitary and unsightly, and the rough surface ordinarily presented externally of the radiator is not favorable to radiation.

The substitution of sheet steel or so called sheet iron for the cast metal has been attempted, but with little success on account of the slight resistance presented by this material to the corrosive action of water and the various chemicals contained in the water which is available for use in domestic and other heating plants. Further, such radiators can not be made of one piece of metal and it has been found difficult to so join the metal sheets as to avoid leakage at the joints due to corrosion or to deflection and straining on account of contraction and expansion because of variation of internal pressure and crushing or deflection of the radiator units when they are drawn together in assembling.

The object of the present invention is to produce a radiator of sheet steel or other sheet metal which is adapted to resist corrosion for an indefinite period, at least equal to the life of a cast iron radiator, and which consists of plates so joined and so protected internally and externally as to the joints that there is no tendency to leakage either from straining, deflection, crushing or corrosion.

The invention relates to a method of making radiators preferably of sheet iron or sheet steel, for which any other available sheet metal may be substituted, and to the radiator produced in the practice of the method, and to the details of construction of this radiator whereby it is adapted to be so produced. The method of the invention consists in the steps or operations or combination of steps and operations necessary to the production of a radiator which is coated internally and externally with vitreous enamel, the method

of the invention in the preferred form being so devised as to provide for the covering of the sheet metal with a plurality of coats of vitreous enamel which covers completely not only the exposed internal and external surfaces of the radiator, but the edge portions of the sheet metal where they are clinched or otherwise joined in combining the concave metal sheets to produce the hollow units or sections of which the radiator is constructed. The enamel which covers these edge portions being in accordance with one form of the invention utilized as a flux whereby it is caused to contribute to the effectiveness of the welding operation assisting in the fusion of the metal so as to produce a permanent joint which is proof against corrosion for an indefinite period at least equal to and probably exceeding the life of the average cast iron radiator.

It is of interest that while the enamel serves in a satisfactory manner as a flux in joining the edges of the sheet metal plates to form the units or sections that it may also be utilized in a different capacity, i. e., as a cementitious material which intervenes between the clinched edges of the sheet metal plates serving to hold the plates together and seal the seams or joints, the metal not being actually fused in accordance with the general acceptance of the term, the clinched edges of the metal being on the other hand sealed by the fusion and setting of the enamel.

The invention also relates to the details and features of construction whereby the units are to be supported from within as to limit the deflection resulting from the pressure applied thereto in joining the units to assemble the radiator and the deflection due to internal pressure and to other features and details which contribute to the production on a commercial basis of a satisfactory radiator of this type, i. e., one which is coated with vitreous enamel over the entire internal and preferably the entire external surface, the joints being sealed and protected by the enamel and the edge portions of the sheet which are interengaged to form the seams or joints, being preferably coated with enamel as to the portions within the joint or seam.

In the accompanying drawings I have illustrated a radiator constructed in accordance with the method of the invention illustrating construction details of the invention and the practice of the method of the invention, the construction shown embodying the preferred details contributing to the production of a satisfactory enameled radiator of the type which is coated internally and preferably externally with vitreous enamel.

In the drawings:

Figure 1 is an end elevation of an assembled radiator.

Figure 2 is a side elevation of the same, broken away to show a portion in section.

Figure 3 is a section on the line 3, 3 of Figure 1 broken away intermediately for convenience of illustration and showing the condition of the enamel internally and externally after baking.

10 Figure 4 is a fragmentary section on the same line showing one of the joints or seams immediately after clinching the edges of the concave metal sheets and prior to application of the external coating, the edges not having been welded.

15 Figure 5 is a section on the line 5, 5 in Figure 1 of an assembled radiator of three or more sections, showing the manner of connecting the units or sections at the top and bottom.

20 Figure 6 is a section through one of the seams by which the edges of the sheet metal plates are joined showing the type of seam in which the enamel is utilized both as a sealing means and as a means for securing the clinched edges of the sheet metal plates to form the unit, the plates being not necessarily otherwise connected by welding. The figure also shows the sheet metal portion of the radiator including the joint coated inside and out with vitreous enamel which has been baked and fused in position thereon.

25 30 Figure 7 is a similar section corresponding to Figure 4 showing a completed seam the edges of the plates being welded, the seam being sealed from within by means of the enamel, the radiator being coated internally with the enamel which has been baked and fused in position thereon.

35 Figure 8 is a fragmentary section corresponding to Figure 5, showing a modification.

Referring to the drawings by numerals, each of which is used to indicate the same or similar parts in the different figures, the construction shown is in its general outline very much like the cast iron radiators in general use consisting of a number of units or hollow sections having registering openings in the lateral faces at the top and bottom, the units being assembled by drawing them together with these openings in registration.

40 The radiator indicated in a general way by reference character 1 consists of any desired number of hollow members or units 2, 2', 2'', which are preferably like or similar to the cast iron radiator units of the present existing practice as to their external outline and somewhat similar to them in the manner of connection except as to 45 the variation of details provided in accordance with the invention to adapt the enameled sheet metal construction of the invention to use in the production of heating radiators.

45 In accordance with this practice, the hollow units or sections 2 are provided with opposite aligned openings 3 and 4 at the top and 5 and 6 at the bottom. In assembling the radiator a suitable number of units 2 are placed with their openings 3, 4, 12, 13 in registration and drawn together by suitable tension members 7 and 8, the tension members 7 and 8 being preferably threaded at their ends at 9 and 9' to engage frusto conical fittings or plugs 10 at the top and 11 at the bottom, which are seated in the flanged openings 70 3, 12, respectively, at the top and bottom of the radiator. These openings 3, 12 are shown as internally flanged at 14, 15, the flanges being turned inwardly and of frusto conical shape to fit the plugs 10 and 11, and each plug is apertured and threaded at its inner end to engage the threads

9, 9' on the ends of the tension members 7, 8. In the form of the invention shown the plug 10 at the top is solid and the plug 11 at the bottom is apertured in the direction of the axis and threaded to engage a steam or water pipe 16, the plug or fitting 11 being apertured laterally at 17 to connect the pipe with the inside of the radiator, the end of the pipe being closed by the tension rod 8. It will be understood that the solid and apertured plugs may be interchanged to give any desired method of connecting the radiators to the system.

80 In accordance with the preferred form of the invention shown, the units or sections 2 are made with the openings at the top and bottom internally flanged as to the openings at one side, opening 3 being internally flanged at 14, opening 12 at 15, and the openings at the other side, i. e. the right hand opening at the top of unit 2 indicated by reference character 4, having an externally disposed flange 18 which is frusto conical as in the previous instance. This flange is surrounded by an annular cavity 19 which provides for the reception of a gasket or fibre ring 20. The opening on the right hand side of this section or unit 2 at the bottom being exactly like the opening 4 at the top is indicated by reference character 4' and need not be further described. The second unit or section 2' and the remaining units or section 2'' need not be further described except that they are assembled in alternating relation so that the internal flanges face the external flanges.

90 The frusto conical fitting or plug 10, at the top, duplicated at the opposite end of the series of units or sections 2 composing the assembled radiator, the duplicate plug being indicated by 10', and the tension member 7 is passed through the registering openings 3, 4, etc. from one end to the other of the complete radiator, being engaged at its opposite ends by the frusto conical plugs 10, 10' which are turned up by means of a wrench to tighten the units or sections in their assembled relation. It is also of interest that the openings 3, 3' are surrounded by an annular seat or aperture 21 in which is seated a fibre ring or gasket 22, which is covered by brass or other sheet metal washer 23 which may be coated with enamel and the plugs or fittings 10, 10', 11, etc. are made of non corrosive metal and ground, the openings 3, 3' being similar openings, if desired, ground as to the enamel therein in frusto conical form to fit and receive the plugs.

100 It will be noted that the joints between the radiator sections at the top and bottom are each formed by and with an externally flanged and an internally flanged opening 3, 3', 4, 12, 13, so that the adjacent openings are of opposite taper, it being understood that all of these openings are of increasing diameter from the inside outwardly, and each section is connected to the adjacent one by means of a double frusto conical fitting 24 having a longitudinal axial aperture at 25 and a central peripheral flange 26, the flange being of such diameter as to fit into the annular space 19 and bear against the gasket or ring 20 so that when the sections are drawn together by taking up on tension members 7, 8 with sufficient pressure a tight joint is formed without any tendency to distort the units.

110 It is also of interest that the sections are further braced and held against distortion due to the tension applied in assembling them by means of tubular struts 27, two of which are contained within each unit or section, one at the top and the other at the bottom. These hollow struts are apertured laterally at 28, the apertures being

150

elongated and spaced around the periphery of the struts which are of sufficient diameter at each end to take over and enclose the annular shoulders 29 surrounding the seats or cavities 19, 21, etc.

5 In this way the tension of the tie rods or tension rods 7 and 8 is directly resisted and taken up preventing absolutely any tendency to distort the units due to the pressure applied in assembling.

The structure having been thus described with 10 the improved details which assist in applying enameled sheet metal to the production of heating radiators, the manner of producing and the details of construction of the hollow enameled sheet metal units to which the important features of 15 the invention relate will now be described. Each unit or section in the form of the invention shown consists of two concave metal plates 30, 31, the curvature being so arranged and selected as to cause the plates when joined at their edges in any 20 suitable manner, to enclose a cavity corresponding to a radiator unit or section of the desired size and shape. Each of these plates 30, 31 has its edges flanged at 32, 33 in a single flat place in a manner suitable to provide for connecting the 25 plates by clinching as shown at 34 in Figures 3, 4, 6 and 7. The first step in the performance of the method which is the subject of the invention is the formation of these sheet metal sheets into the sections 30, 31 as described, the flanges being 30 preferably of different widths and in any suitable form either straight or partially turned. The plates thus formed are first coated on the inside with a vitreous enamel paste 35 of the kind which is adapted to be baked on the metal whereby it is fused and subsequently permitted to harden as an 35 integral sheet or coating of vitreous enamel. For the purposes in hand the most flexible elastic compounds of enamel which can be obtained or produced are most satisfactory, a considerable 40 content of borax being desirable when the enamel is employed as a flux.

The manner of initial coating is best illustrated in Figure 4. This is preferably applied before any bending or clinching of the edges. 45 The metal sheets are then baked to set the enamel 35 on the inside, which may consist of any desired number of coats. The metal sheets are then joined by clinching the edges 32, 33, as particularly illustrated in Figure 4, after which 50 the units or sections are joined by welding at 43 as shown in Figure 7, i. e., by running an electric welding tool along the clinched edges 32, 33, or along exposed edge 32' in any suitable manner. The section is then coated externally 55 with enamel paste, it being understood that several coats of this enamel are applied, and that all necessary precautions are taken to completely cover the joints and to fill in the angles and 60 depressions as best illustrated at 37 and 39. Extra 65 coatings of the enamel paste are applied at these points, if necessary, it being understood that each coat of enamel is preferably allowed to dry before the next is applied. This portion 70 of the method may be performed in any manner which may be found most suitable to the desired result and to the material used. When the coating 75 operation has been completed, the various angles and depressions being covered as aforesaid, the unit is finished by placing it in an oven, heating the enamel to a sufficient temperature to fuse it, after which it is permitted to cool and 80 harden, forming an integral vitreous coating, covering the inside and the outside of the unit completely. It is of particular interest that the 85 enamel when thus fused completely closes and

seals the joints or seams on the inside at 38 and on the outside it seals the crevices and depressions around the joint as at 37 and 39 giving a smooth external contour. The foregoing is the preferred method.

Referring now to Figure 6, it is of interest that the joint may if desired be sealed and completed, the welding step being omitted the unit or section in detail in Figure 6 being merely placed in the oven and heated to a temperature at which the enamel is completely fused, after which it is permitted to cool and harden. By this method the enamel is hardened between and around the clinched edges of the sheet metal 32, 33, 34, as indicated at 40. The joint is sealed on the inside as indicated at 41 and on the outside the crevices and depressions are completely filled and reduced to a pleasing and satisfactory curvilinear contour as indicated at 42.

Figure 8 shows an alternative form of interlocking means whereby the fittings 10, 11, 24, etc., i. e., the frusto conical plugs and the double frusto conical plugs may be omitted, the adjacent radiators being provided with male and female guiding sleeves, 45, 46 as to their adjacent 95 contacting portions, the respective male and female members being surrounded by annular cavities 47, 48 which when placed in registration by engagement of the male and female members 45, 46, form a single annular cavity 49 which is 100 adapted to contain a packing ring or gasket 50, which serves as a yielding means between the radiator sections to close contact between the 105 seams, and take up the pressure applied to the radiator sections or units in holding them in 110 assembled relation. The crushing pressure thus applied to the units in assembling them is taken up by hollow struts 51, corresponding to the struts 27 in Figure 5, any suitable tension means as the rod 52, the nuts 53 being available for 115 this purpose.

The method of the invention whereby radiators coated with enamel internally and externally composed of sheet steel plates joined at their edges which are concealed by means of the 120 enamel which may assist as a cementitious material in the permanent fastening of the plates and/or may act as a flux in joining them by welding is of primary importance as a feature of the invention, as is also the radiator of the 125 invention composed of sheet metal and protected by enamel internally and externally, the radiator units being as already pointed out preferably composed of concave sheet metal plates welded or otherwise permanently joined at their edges 130 and sealed externally and internally by means of the vitreous enamel. The invention also includes, as already pointed out, the details of structure whereby a sheet metal radiator coated internally and externally with vitreous enamel 135 composed of units as described is adapted for assembly in series of such units in proper registration and suitably connected to form complete radiators for use in connection with domestic heating plants and for heating plants for heating 140 rooms, apartments or buildings for human occupation.

It is of interest that all of the metal portions including hollow studs or struts 27, the washers 23, and even the fittings 10, 11 and 24 and the 145 tension rods 7 and 8 may be coated with vitreous enamel to prevent any and all possibility of corrosion. This also adds to the pleasing effect as the external view shows nothing but the enamel surface unless it is preferred to finish the plugs 150

10, 11 which are exposed externally with nickel or chromium or similar bright non corrosive metal.

Various advantages of the invention as the

5 lightness, cheapness, efficiency, quick response to control, etc., due to quick heating and improved radiation, improved appearance, increased sanitation and the like have been fully pointed out, discussed and emphasized in the preamble.

10 I have thus described a method of making heating radiators of sheet metal, coated with enamel internally and externally, and sealed as to the seams or joints, and an article made in accordance with the method of the invention, the description being specific and in detail in order that the method of practicing the invention and operating, applying and using the same may be fully understood, however, the specific terms herein are used descriptively rather than in a limiting sense, ²⁵ the scope of the invention being defined in the claims.

What I claim as new and desire to secure by Letters Patent is:

1. The method of making radiator sections or units which consists in providing concave metal sheets, coating them internally with vitreous enamel paste, placing the sheets with the concavities in registration and the edges in contact, joining the edges to form a hollow radiator section, coating the sections externally with enamel paste and baking to fuse the enamel and form an integral vitreous external and internal coating for the radiator sections whereby the said edges are sealed externally and internally by and with the enamel.

2. The method of making radiator sections or units which consists in providing concave metal sheets, coating them internally with vitreous enamel paste, placing the sheets with the concavities in registration and the edges in contact, welding the edges to form seams joining the metal sheets, coating the sheets externally with enamel paste and baking, to fuse the enamel and form

an integral vitreous external and internal coating for the radiator unit whereby the seams are sealed externally and internally by and with the enamel.

3. The method of making a sheet metal radiator which consists in forming concave metal sheets, coating the inner surface with enamel paste and placing the concave sheets in registration to form a hollow unit clinching and welding the edges and coating the external surface with enamel paste baking to fuse the enamel forming a continuous vitreous coating and sealing and protecting the joints. 80

4. The method of making radiators which consists in forming concaved sheet metal sections adapted to be joined at the edges to form hollow units to be assembled in the production of a complete radiator coating the sections and edges internally with vitreous enamel paste, placing the sections in registration having their pasty edge portions in contact, joining the edges by crimping and welding the overlapping edges, whereby the enamel paste on said overlapping edge is utilized as a welding flux, coating the radiator externally with enamel paste and heating to fuse the enamel whereby it is caused to form an integral vitreous coating, sealing the joints or seams at the edge of the plates. 85

5. The method of making radiator units or sections which consists in providing concaved metal sheets adapted to be assembled by joining them at the edges to form hollow units, coating the sheet metal plates and edge portions internally with vitreous enamel paste, placing the sections in registration with their coated edges in contact to form a hollow radiator unit, crimping the edges together forming a seam whereby the metal sheets are joined, coating the external surface with enamel paste and baking to fuse the enamel and permitting it to cool, forming a vitreous coating 100 whereby the seams or joints are sealed. 90
